Primary Examiner—Cathron C Brooks*Assistant Examiner*—Kevin K Rudzinski(74) *Attorney, Agent, or Firm*—Clifford O. Chi(57) **CLAIM**

The ornamental design for an LED lens, as shown and described.

DESCRIPTION

FIG. 1 is a perspective view of an LED lens of the present invention.

FIG. 2 is a front elevational view of the LED lens of FIG. 1.

FIG. 3 is a rear elevational view of the LED lens of FIG. 1.

FIG. 4 is a left-side, elevational view of the LED lens of FIG. 1.

FIG. 5 is a right-side, elevational view of the LED lens of FIG. 1.

FIG. 6 is a top plan view of the LED lens of FIG. 1; and,

FIG. 7 is a bottom plan view of the LED lens of FIG. 1.
